UNITED STATES PATENT OFFICE.

HERMAN F. BALL, OF NEW YORK, N. Y.

CHAFING DEVICE FOR RAILWAY DRAFT-GEAR.

1,130,462.

Specification of Letters Patent. Patented Mar. 2, 1915.

Application filed March 3, 1914. Serial No. 822,883.

To all whom it may concern:

Be it known that I, HERMAN F. BALL, a citizen of the United States, residing in the borough of Manhattan, in the city, county, and State of New York, have invented a certain new and useful Improvement in Chafing Devices for Railway Draft-Gear, of which improvement the following is a specification.

This invention relates to draft appliances for railway vehicles, and more particularly to chafing block devices adapted for use between the ends of a locomotive and tender for transmitting buffing stresses from one vehicle to the other. A device of this type is set forth in my prior application Serial No. 771,143, filed June 2, 1913, in which the proximate ends of the vehicles are provided with convex chafing plates between which is located a laterally movable wearing block having double concave surfaces coöperating with the curved surfaces of said chafing plates, one of said chafing plates having an adjustable wedge for taking up the wear of the parts. In a radial chafing device of this type, the proper operation of the same, when passing around curves, is dependent upon the close contact of the concave surface of the floating block with the coöperating convex surfaces of the chafing plates, and it is therefore important to take up the lost motion due to the wear of the draw bar upon the pins, which might otherwise cause the chafing surfaces to get out of true contact with each other and produce a lagging movement of the floating block which would be very detrimental to the proper action of the device and might allow the block to become jammed between the convex surfaces of the two chafing plates.

The object of my present invention is to provide improved yielding and elastic means, such as a spring, for automatically adjusting one of the chafing plates and taking up all lost motion within certain limits due to the wear of the draw bar, and thus maintain the coöperating concave and convex surfaces in a close and true contact which is also to some extent yielding, thereby providing a certain amount of flexibility in the connection.

The improvement claimed is hereinafter fully set forth.

In the accompanying drawings: Figure 1 is a vertical longitudinal section of the adjacent ends of two railway vehicles, such

as a locomotive and tender, with my improvement applied thereto; Fig. 2, a half plan and half horizontal section of the same; Fig. 3, a vertical longitudinal section of the chafing device taken on the line 3—3 of Fig. 2; and Fig. 4, a half plan and half horizontal section of the wedge and adjustable chafing plate with the spring and plate in the extended position.

According to the construction shown in the drawing, my improvement is illustrated as applied to the draft gear of a locomotive and tender, comprising a draw bar, 1, coupled to the locomotive by a pin, 2, passing through the sill plate, 3, and coupled to the tender by a pin, 4, mounted in a casting secured to the end sill, 5. The draft or pulling stresses are transmitted through the bar, 1, but for transmitting the buffing or pushing stresses, chafing devices are provided between the end sills of the respective vehicles. These devices comprise a chafing plate or casting, 6, bolted, or otherwise secured, to the end sill of one of the vehicles, 80 as the locomotive, and having an outer convex surface formed on a curve with the pin, 2, as a center and a chafing plate, 8, mounted on the other vehicle, or tender, and having a similar convex surface formed 85 on a curve with the pin, 4, as a center. Between the adjoining convex surfaces of the respective chafing plates is mounted the chafing block, 9, having double concave surfaces engaging with the respective convex 90 surfaces of the chafing blocks, and coöperating therewith in such a manner as to move radially or transversely thereon when one vehicle turns at an angle with respect to the other, as when passing around curves. 95 In this way the chafing block surfaces remain in contact with the corresponding surfaces of the chafing plates throughout substantially the full length of said block, which occupies a position in line with the vertical plane of the draw bar at all times and transmits all of the pushing stresses from one vehicle to the other through said engaging surfaces.

For the purpose of manually adjusting one of the chafing plates at certain intervals to compensate for the wear of the parts, the chafing plate, 8, is mounted in the open ended housing, 7, bolted to the end sill, 5, of the tender, and the wedge, 10, is inserted between the back of said plate and the base of the housing for adjusting said chafing

plate longitudinally. A bolt, 11, passes through corresponding holes in the housing, 7, and in the wedge, 10, for holding the same in position, and the wedge is provided with a plurality of holes for adjusting the same transversely to its different positions.

In order to automatically maintain the bearing surfaces in close contact even in the case of neglect to manually adjust the wedge, the chafing plate, 8, is provided with a cavity, 13, containing the flat leaf spring, 12, and the spring block, 14, having its rear face inclined to engage the wedge, and its outer surface curved to engage the leaf springs when the same are drawn up to the compressed position, as indicated in Fig. 2. The springs thus act between the spring block at the back and the lugs within the cavity of the chafing plate bearing against the opposite ends of said springs so that a certain amount of lost motion due to the wear of the draw bar or other parts will be automatically taken up by the expansion of the leaf spring and the setting forward of the chafing plate, 8, until the springs reach their straight position, as shown in Fig. 4. The springs are of sufficient strength to yieldingly hold the co-operating curved surfaces in proper contact with each other but are not intended to absorb the buffing stresses which are transmitted directly from the fixed chafing plate, 6, through the block, 9, and the movable chafing plate, 8, to the wedge, 10, and housing, 7.

Having now described my invention, what I claim as new and desire to secure by Letters Patent is:

1. In a draft gear for railway vehicles, the combination of a draw bar pivotally connected at its ends to the respective vehicles, two chafing plates, each connected to the end of a vehicle, and having convex outer surfaces, an interposed floating chafing block having double concave faces co-operating

with the convex faces of the adjoining chafing plates, one of said chafing plates being longitudinally adjustable, and having a cavity, and a spring located in said cavity.

2. In a draft gear for railway vehicles, the combination of a draw bar pivotally connected at its ends to the respective vehicles, two chafing plates, each connected to the end of a vehicle, and having convex outer surfaces, an interposed floating chafing block having double concave faces co-operating with the convex faces of the adjoining chafing plates, one of said chafing plates being longitudinally adjustable, and having a cavity, and a spring block and leaf springs located in said cavity.

3. In a draft gear for railway vehicles, the combination of a chafing plate having an outer convex surface, another chafing plate also having a convex surface, a floating chafing block having double concave surfaces interposed between said chafing plates, one of said chafing plates being longitudinally adjustable, a transverse wedge for adjusting said chafing plate, and a spring acting between the wedge and said adjustable chafing plate.

4. In a draft gear for railway vehicles, the combination of a draw bar pivotally connected at its ends to the respective vehicles, and having convex outer surfaces, an interposed floating chafing block having double concave faces co-operating with the convex faces of the adjoining chafing plates, one of said chafing plates being longitudinally adjustable, and having a cavity, a transverse wedge for adjusting said chafing plate, a spring block located in said cavity and bearing against the wedge, and a spring acting between said spring block and the adjustable chafing plate.

HERMAN F. BALL.
